[57] CLAIM

The ornamental design for a toy rocking kangaroo, as shown and described in the accompanying drawings.

DESCRIPTION

FIG. 1 is a side perspective view of a toy rocking kangaroo showing my new design;

FIG. 2 is a top plan view thereof;

FIG. 3 is a bottom plan view thereof;

FIG. 4 is a side elevational view thereof;

FIG. 5 is a side elevational view of the side opposite that shown in FIG. 4;

FIG. 6 is a front elevational view thereof; and

FIG. 7 is a rear elevational view thereof.

FIG. 6

FIG. 7
